ANTONIO BAGUTTI, OF TURIN, ITALY.

VIBRATORY BELL.

1,244,013.

Specification of Letters Patent. Patented Oct. 23, 1917.

Application filed November 26, 1913. Serial No. 503,342.

To all whom it may concern:

Be it known that I, ANTONIO BAGUTTI, subject of Italy, residing at Turin, via Monteverchio, 11, Italy, have invented new and useful Improvements in Vibratory Bells, of which the following is a specification.

Heretofore the usual form of electric vibratory bells have been adapted for use on low voltage circuits, mainly on account of the limitation imposed by sparking between the interrupter contacts. Thus a battery consisting of a few cells has generally been used as the source of current supply, even though the comparatively frequent renewals required and the unreliability of the system, are recognized disadvantages. To avoid this trouble, transformers have been used to reduce the voltage of electric power and lighting circuits to the low value suitable for these bells, but in this case, the primary winding of the transformer remains connected to the power or lighting circuit and thus continually absorbs electric energy therefrom.

In accordance with my invention, both the batteries and the transformers are eliminated, by constructing the vibratory bell and arranging the vibratory element in the structure so that the bell operates reliably on electric circuits of 125 volts, 250 volts, or even higher, without objectionable sparking at the interrupter contacts.

In the accompanying drawings, illustrating the preferred form of my invention,

Figure 1 represents a plan view partly in section, with the gong removed;

Fig. 2 represents a vertical section on line 2-2 of Fig. 3 with the gong in place; and Figs. 3 and 4 are views showing the details of construction of the circuit interrupter, Fig. 3 being a section on line 3-3 of Fig. 1, and Fig. 4 being a section on line 4-4 of Fig. 3.

The base plate 1 is provided with holes 2 and 3 for fastening the bell in place, and with holes 4 and 5 for the passage of electric wires therethrough. The U-shaped member 7 of cast iron, steel, or other magnetic material, is integral with the base plate, and is also integral with an upstanding arm 6 which carries a screw-threaded lug at the top for holding the gong 8 in place. The insulated magnet spiral 10 is hollow and of cylindrical form. It is held in place between the arms of the U-shaped member 7 by

means of a brass pipe 11. This pipe is flanged at one end, and is screw-threaded at the other end. The iron nut 12 engages the screw threads of the pipe 11, and is also provided with other screw threads adapted to engage the iron plug 13. This plug projects within the pipe 11 and is adjustable in the nut along the length of the pipe. An iron tube 15 forming the armature of the magnet extends within the core of the magnet coil so as to be reciprocative therein toward and away from the adjustable abutting plug 13. A plug 16 is suitably fastened within the outer end of the armature, and this plug 16 carries a disk 17 of insulating material, on the outer face of which is a copper plate 18, the disk 17 and the plate 18 being secured to the plug 16 in any suitable way. The armature 16 and plug 16 are slotted as best shown in Fig. 3 so as to provide for the passage loosely therethrough of the pin 34, whether this pin be in the position shown by the full lines, or in the position indicated by the broken lines in Fig. 1. This pin 34 connecting arm 34 is carried by a rectangular brass piece 31, which, pivoted on a copper pin 30 between lugs projecting from the end of the U-shaped member 7, works as a lever arm and is provided with a spring 32 and a clapper 33. The spring carries the clapper at one end and rests at the other end against a face of the U-shaped member 7. The arrangement of this spring is such that when the pivoted lever 31 is in the inclined position shown in broken lines in Fig. 3, the spring 32 takes the position also shown in broken lines in that figure and is under stress tending to return the clapper 33 from the position shown in broken lines to its normal position shown in full lines. A plate 23 of insulating material is fastened by the bolts 21 and 22 to an arm of the U-shaped member 7, and to this plate 7 are suitably fastened two T-shaped copper plates 24 and 25 insulated from each other and having binding posts 39 and 40. The copper plate 18 normally bridges the copper plates 24 and 25, as shown best in Figs. 3 and 4. The interruption of the electric circuit occurs between the copper plate 18 and the copper plates 24 and 25, and thus the electrical circuit is interrupted in the field of magnetic flux passing between the armature 16 and the U-shaped member 7.

In Fig. 1, 36 and 37 are intended to

represent an electric lighting or power circuit of 125 volts, 250 volts, or even higher, and wire 36 is connected to one terminal of the magnet coil 10, and thence through the magnet to the binding post 40 of the contact plate 25, while the wire 37 is connected through the push button or switch 38 to the binding post 39 of the contact plate 24, all as indicated in Fig. 1. Thus when the push button or switch 38 is closed, the current passes through the magnet coil 10, and the plug 13 being magnetized thereby attracts the armature 15. This movement of the armature disengages the copper plate 18 from the plates 24 and 25 and thereby interrupts the current through the magnet winding. This movement of the armature swings the pivoted lever 31 from the position shown in full lines in Fig. 1 to the position shown therein in broken lines, and thereby brings the clapper 33 into contact with the gong. The spring 32, then under stress, returns the parts to their normal positions, wherein the copper plate 18 again closes the circuit through the magnet winding. The vibrating action set up in this manner continues until the push button or switch 38 is opened.

An essential feature of this invention resides in the arrangement by which the armature is located over the pole of the electromagnet. If desired, the armature may be arranged in the same manner in the interior of a magnetic ring.

The phrase "vibratory bell", used hereinbefore and in the appended claims is intended to include also vibratory buzzers, interrupters, and the like.

Having thus described my invention, what I claim is:

- 40 1. In a vibratory bell, an electromagnet, a reciprocative armature magnetically responsive thereto, a rocking member operatively connected to the reciprocative armature so that as the armature reciprocates the rocking member oscillates; a resilient arm secured intermediate its ends to the rocking member whereby lengths of the arm on opposite sides of the rocking member are alternately flexed during operation of the bell, and circuit connections including the winding of the electromagnet and interrupting means carried by the reciprocative armature; substantially as described.
- 45 2. In a vibratory bell, an electromagnet, a reciprocative armature magnetically responsive thereto, a rocking member operatively connected to the reciprocative armature so that as the armature reciprocates the rocking member oscillates, a resilient arm carried by the rocking member and carrying the clapper, a pin operatively connecting the rocking member and the reciprocative armature, the armature having a recess and the pin being rigidly fastened to the rocking member and loosely engaging the recess, and circuit connections including the winding of the electromagnet and interrupting means carried by the reciprocative armature; substantially as described.

reciprocative armature magnetically responsive thereto, a rocking member operatively connected to the reciprocative armature so that as the armature reciprocates the rocking member oscillates, a resilient arm carried by the rocking member and carrying the clapper, a pin operatively connecting the rocking member and the reciprocative armature, the armature having a recess and the pin being rigidly fastened to the rocking member and loosely engaging the recess, and circuit connections including the winding of the electromagnet and interrupting means carried by the reciprocative armature; substantially as described.

3. In a vibratory bell, the combination with the hollow bell-shaped gong, of an electromagnet housed within the gong, a reciprocative armature magnetically responsive thereto, a long leaf spring for carrying the clapper arranged substantially parallel with the rim of the gong and bent so as to conform approximately to the adjacent periphery of the gong, a bell crank lever actuated by the armature and having an arm angularly connected to the leaf spring and which is very short as compared to the leaf spring, and circuit connections including the winding of the electromagnet and interrupting means carried by the reciprocative armature; substantially as described.

4. In a vibratory bell, the combination with the hollow bell-shaped gong of a rigid yoke housed under the gong and arranged with its base parallel to the plane of the rim of the gong, an electromagnet with its axis parallel to said plane, the electromagnet having a hollow core and being embraced by the yoke, a vibratory arm pivoted to the yoke, a reciprocative armature within the hollow core of the electromagnet for operating the vibratory arm, and circuit connections including the winding of the electromagnet and interrupting means carried by the reciprocative armature; substantially as described.

In testimony whereof I have signed my name to this specification in the presence of two subscribing witnesses.

ANTONIO BAGUTTI.
